UNITED STATES PATENT OFFICE.

WINTON A. DEAN AND ARTHUR L. DEAN, OF LONG BEACH, CALIFORNIA.

ROTARY MIXING DEVICE.

Application filed November 8, 1927. Serial No. 231,887.

The object of the present invention is to provide a novel device adapted to be mounted between the intake manifold and the carburetor of an internal combustion engine, to facilitate the mixture of air and gas as the air and gas pass from the carburetor to the manifold, a thorough vaporization of the fuel being brought about.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in section, a device constructed in accordance with the invention, parts being in elevation;

Figure 2 is a section on the line 2—2 of Figure 1;

Figure 3 is a section on the line 3—3 of Figure 2.

The numeral 1 marks the parts of a conduit leading from the carburetor of an internal combustion engine to the intake manifold thereof. The parts 1 of the conduit have flanges 2 between which is located a casing 3. Securing elements 4, such as bolts, pass through the flanges 2 and through the casing 3, to hold the casing in place between the flanges, as shown in Figure 1 of the drawings. The casing 3 may conveniently be made out of laterally separable parts 5 held together by the bolts 4.

In the casing 3 there is formed a chamber 6, and the casing has oppositely disposed reduced openings 7 communicating with the chamber 6, the openings 7 being of approximately the same diameter as the bore of the conduit 1. Cross pieces 8 are connected to the casing 3 and extend across the openings 7. In one of the cross pieces 8 an adjustable bearing 9, preferably a screw, is mounted, and the bearing 9 is held in any position to which it may have been adjusted, by

means of a nut 19 threaded on the bearing, and adapted to engage the corresponding cross piece 8. In the opposite cross piece 8, one end of a shaft 10 is journaled, the opposite end of the shaft 10 being journaled in the adjustable bearing or screw 9.

On the shaft 10 is mounted a rotor which is a composite structure. The rotor includes a foraminous body 11 on one side of which are trough-shaped vanes 12, that overhang the foraminous body as shown clearly in Figure 3, the vanes 12 extending outwardly from a central hub 14. As shown at 15 in Figure 2 of the drawings, the vanes 12 are curved, in any desired way, in a direction parallel to the body 11 of the rotor, so that the fuel and air will be directed by the vanes 12 toward the center of rotation of the rotor 11, that is, toward the axis of the shaft 10. On the opposite side of the rotor 11 from the vanes 12, are located blades 16 connected to a central hub 18. The blades 16 are disposed radially from the rotor 11, as shown in Figure 2. The blades 16 are connected along one longitudinal edge with the foraminous body 11, but, considered transversely, they slant away from the body 11, so that the opposite edge of each blade 16 is at some distance from the body 11, as clearly shown in Figure 3. Nuts 17 are threaded on the shaft 10 and engage the hubs 14 and 18 to hold the hubs, and the corresponding vanes and blades, in place on the foraminous body 11 of the rotor.

The current of air and fuel passing through the conduit 1, turns the rotor. The vanes 12 carry the mixture inwardly toward the axis of rotation of the rotor, and the blades 16 tend to force the mixture outwardly away from the center of rotation of the rotor. In this way, a thorough mixture of fuel and air is brought about.

What is claimed is:—

In a rotary mixing device, a casing, a rotor located in the casing and including a foraminous body, hubs on opposite sides of the body, vanes on one side of the body and joined to one hub, the vanes extending outwardly to a point adjacent to the periphery of the rotor, the vanes being trough-shaped from their outer ends to the said hub and being so inclined, in a direction at right angles to the axis of the rotation of the rotor, as to carry

the fuel mixture toward the center of rotation of the rotor; and blades located on the opposite side of the body and joined to the outer hub, the blades being inclined transversely at an acute angle with respect to the body and being disposed in substantially radial relation with respect to the axis of rotation of the rotor, and means cooperating

with the hubs for supporting the rotor for turning movement within the casing. 10

In testimony that we claim the foregoing as our own, we have hereto affixed our signatures.
